UNITED STATES PATENT OFFICE.

JOHN T. JANETTE, OF CHICAGO, ILLINOIS.

DESIGN FOR A CASING FOR AIR-PUMPS.

50,149.

Specification for Design.

Patented Jan. 9, 1917.

Application filed October 16, 1916. Serial No. 126,047. Term of patent 7 years.

To all whom it may concern:

Be it known that I, JOHN T. JANETTE, a citizen of the United States, residing at Chicago, in the county of Cook and State of Illinois, have invented a new, original, and ornamental Design for a Casing for Air-Pumps, of which the following is a specification, reference being had to the accompanying drawing, forming a part thereof.

The figure shown in this drawing is a perspective view of a casing for air pumps of

the type commonly used as beer pumps, showing my new design.

The base of this casing is made of opaque material and in the unique form shown, while the upper portion is made of glass, which exposes the upper part of the base portion.

I claim:

The ornamental design for a casing for air pumps, as shown.

JOHN T. JANETTE.
